UNITED STATES PATENT OFFICE.

ALBERT E. BRICKER, OF ROCHESTER, NEW YORK.

MUFFLER.

Application filed July 17, 1919. Serial No. 311,560.

To all whom it may concern:

Be it known that I, ALBERT E. BRICKER, a citizen of the United States, and resident of Rochester, in the county of Monroe and 5 State of New York, have invented certain new and useful Improvements in Mufflers, of which the following is a specification.

The present invention relates to mufflers for the fluid discharges of steam, gas, air or 10 the fluid motors and more particularly to the type in which the muffler is provided with a passageway formed by a plurality of chambers in which the fluid successively expands, an object of this invention being to 15 provide a construction which does not create any back pressure while at the same time eliminating all sound due to the discharge.

To this and other ends, the invention consists of certain parts and combinations of 20 parts, all of which will be hereinafter described, the novel features being pointed out in the appended claims.

In the drawings:

Fig. 1 is an axial section through a muffler designed for a steam engine in which the muffler is shown as being connected to the exhaust of the engine;

Fig. 2 is a section on the line 2—2, Fig. 1;

Fig. 3 is a detail view of the intake end of 30 the muffler;

Figs. 4 and 5 are side elevations partly in section of two interior walls of the muffler; and

Fig. 6 is a view in side elevation of the 35 muffler.

It has been suggested prior to this invention to provide in a muffler a passageway formed by a plurality of successive chambers into which the discharge fluid is conducted 40 and expanded. In prior constructions of this type, it is necessary especially in steam mufflers to restrict the passageway between the different chambers to openings having areas less than twice the intake of the steam 45 to the engine if any muffling action is to be obtained and, in so restricting the areas between the chambers, a back pressure is produced by the muffler.

According to this invention, a structure 50 is provided in which the area of the openings between the successive chambers may be at least two and one-half times the area of the intake to the engine so that no back pressure will be present in the muffler, provision being made at the intake of the muffler for di-

viding the fluid into jets or streams which are caused to travel one against the other in opposite directions and in this way prevent the noise or sound in the exhaust.

Referring to the embodiment of the invention herein shown, the muffler comprises an outer casing formed by two sections 1 internally threaded at their ends, their adjacent ends being connected by an externally threaded sleeve 2. The intake end 3 connects with the engine 4 and the outlet end 5 connects if desired with an outlet pipe 6. The passageway through the muffler is, in this instance, formed by a hollow frustro-conical member 7 surrounding a tubular member 8 providing an expansion chamber 9 between them. At the end adjacent the intake of the muffler, a partition 10 is provided which is preferably in the form of a disk externally threaded and engaging internal threads on the frustro conical member 7. This disk is provided with an opening 11 surrounded by an externally threaded bore 12, the walls of which engage with the internal threads on the lower end of the 80 tubular member 8. The opposite end of the frustro-conical member 7 has a cylindrical bore 13 which snugly fits the adjacent end of the tubular member 8 so that the chamber 9 is closed at both ends. The opening 11 in the partition 10 forming the intake to the passageway through the muffler has a diameter less than the internal diameter of the tubular member 8 so that the fluid passing through the intake opening 11 expands into 85 the chamber 14 formed by the tubular member 8 near its opposite end. The tubular member 8 is provided with outlets 15, the cross sectional area of all of these outlets combined being about two and one-half 90 times the cross sectional area of the inlet to the steam engine (not shown) and the cross-sectional area of the intake opening 11 being also preferably two and one-half times the area of the inlet to the steam engine. The frustro-conical member 7 rests at one 95 end against an internal annular shoulder 16 near the intake end of the muffler. Owing to the shape of the frustro-conical member 7, and its central arrangement within the 100 casing, a chamber 17 is provided about the frustro-conical member 7 and this chamber communicates with the chamber 9 through a plurality of ports or openings 18, the combined cross sectional area of which is sub- 110

stantially two and one-half times the area of the intake opening of the engine. The chamber 17 is closed by a disk 19 which rests against the seat 20 formed adjacent the discharge end of the muffler, this disk 19 also acting to close the adjacent end of the tubular member 8 and to this end having an externally threaded projection 21 which engages internal threads on the tubular member 8. The partition 19 is provided with ports or openings 22, the combined area of which is substantially equal to two and one-half times the area of the intake of the engine. It will thus be seen that the chambered passageway through the muffler does not act to produce a back pressure. However, with such an arrangement there would be a hissing sound produced by the discharge if no means were provided to prevent such sound.

To prevent this hissing sound, means is arranged at the intake of the muffler to divide the fluid into a plurality of streams and to cause said streams to travel in opposite directions one against the other, for it has been found that when two fluid streams are caused to intersect, the hissing sound is eliminated. In this instance, this result is obtained by providing at the intake end of the muffler, an annular chamber 23 in which an annular disk 24 is centrally arranged, this disk having a greater diameter than the intake end 11 of the passageway through the muffler and being spaced from the side wall of the chamber to provide a passageway about said disk, thus producing an annular stream which impinges on the partition 10 and is turned inwardly and rearwardly toward the inner face of the disk 24. The disk is also provided with a central port 25 to form a stream which discharges in line with the opening 11 against the stream passing toward the disk 24 in an opposite direction, lugs or supports 26 being employed for supporting the disk 24 in spaced relation to and from the partition 10.

The muffler is connected to a fluid exhaust and the fluid passes in a stream through the central port 25 of the disk 24 and also around the edges of the disk being deflected toward the disk by the partition 10 about the opening 11. The cross sectional area of these fluid passageways is substantially twice the intake area of the engine so that the disk does not produce any back pressure. The two streams intersect from opposite directions on the opposite face of the disk and then pass through the intake end of the chambered passageway of the muffler. In this passageway, the fluid is caused to expand successively in a number of chambers before being discharged to the atmo-

sphere thus rendering it lifeless when it issues to the atmosphere. Through this arrangement, a muffler is provided which does not create any back pressure and which at the same time eliminates all sounds.

What I claim as my invention and desire to secure by Letters Patent is:

1. An exhaust muffler having at its intake a flat disk provided with a central opening and spaced from the wall of the muffler to provide an annular opening about the edge of the disk and the diameter of the disk being less than the smallest diameter of the intake opening, the muffler also having a passageway beyond said disk of less diameter than the disk and a wall about said passageway beyond the disk and in such a position that the fluid will flow in straight lines through the intake opening around the edge of the disk toward the wall to be deflected rearwardly toward the disk and to intersect from an opposite direction the fluid passing through the central opening.

2. A muffler comprising a casing having two partitions, one of which is formed with a central opening and the other of which is formed by an annular series of openings, a tubular member connecting the partitions and provided with openings near one end, the other end communicating with said central opening in one of the partitions, and a frustro-conical member surrounding said tubular member to provide a chamber about said tubular member and a chamber between the wall of the casing and the frustro-conical member, said last named chamber communicating with the annular series of openings and said frustro-conical member also being provided with openings forming communication between the last mentioned chamber and the chamber that is provided between the frustro-conical member and the tubular member.

3. A muffler comprising two members detachably connected and each provided with an internal shoulder, two partitions each resting upon one of said shoulders, one of said partitions having a central opening and the other an annular series of openings and tubular member connecting the partitions and communicating with the central opening, said tubular member having openings in its walls, and a second member surrounding the tubular member and providing two chambers, one between the wall of the casing and one about the tubular member, said second member having openings in its walls providing communication between the two chambers and the chamber about said second named member communicating with the annular series of openings in the partition.

ALBERT E. BRICKER.
